UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,412, dated August 16, 1881.

Application filed July 18, 1881. Term of patent 3½ years.

To all whom it may concern:

Be it known that I, WALTER J. GADSBY, a subject of the Queen of Great Britain, residing at Boston, in the county of Suffolk and State of Massachusetts, have invented a certain new and original Design for Carpets, of which the following is a specification.

The design is fully shown in the accompanying photographic illustration, forming part of this specification.

The design consists of the figures A and B, representing detached branches or sprays having leaves and flowers thereon displayed upon a ground which is ornamented with minute detached irregular angular and fanciful figures, 15 as shown.

I claim—

The design for a carpet, substantially as herein shown and described.

In testimony whereof I have signed my name 20 to this specification, in the presence of two subscribing witnesses, this 15th day of July, A. D. 1881.

WALTER J. GADSBY.
